UNITED STATES PATENT OFFICE.

ORLANDO K. MORGAN, OF ERWIN, TENNESSEE, ASSIGNOR OF ONE-HALF TO HERBERT H. HART, OF EVANSTON, ILLINOIS.

RAIL-CHAIR.

1,369,183.

Specification of Letters Patent. Patented Feb. 22, 1921.

Application filed December 2, 1919. Serial No. 341,983.

To all whom it may concern:

Be it known that I, ORLANDO K. MORGAN, a citizen of the United States, and residing at Erwin, county of Unicoi, State of Tennessee, have invented certain new and useful Improvements in Rail-Chairs, of which the following is a specification.

Heretofore a number of rail chairs designed and adapted to support both the main traffic rail and a guard rail on railroad curves have been suggested or experimented with, but for various reasons have not come into general use. It is realized by railroad men that for the sake of safety and economy, it is absolutely necessary to employ guard rails on curves to engage the backs of the flanges of the inside wheels of cars rounding the curve. This prevents the outer wheels of the cars from mounting the outside rails and causing a wreck; doubles the life of the outer rail of the curve by decreasing the wear thereon; permits less elevation of the outer rail, and thereby lengthens the life of the inner rail which would otherwise be quickly worn out under the heavy slow moving trains; makes stiffer curves, inasmuch as the track construction is stiffened, and there is less tendency for the curve to straighten out; and equalizing the wear on the inner and outer wheels of the car or train. Realizing these advantages, numerous attempts have been made to discover the cheapest and most satisfactory means for attaching the guard rail to the roadbed and, as before stated, it has been suggested to mount both the inner traffic rail and its guard rail upon the same rail chair. The result of previous efforts along this line have not been altogether satisfactory, the rail chairs devised being generally cumbersome, weighty and expensive to manufacture, or having other defects which prevent their general adoption.

It is the object of this invention to provide a rail chair for use on railroad curves which supports firmly both the main inner traffic rail and its guard rail, maintains them accurately in fixed relationship, which may be used with ordinary standard rails, and does not require a guard rail of special shape, is light in weight, is easily secured to a tie, and is furthermore easily and

cheaply manufactured. The invention will be fully described in the following description when taken in connection with the accompanying drawings, in which—

Figure 1 is a cross section of a portion of a railroad roadbed taken on a curve showing the guard rail and a car axle and wheels mounted thereon;

Fig. 2 is a longitudinal section through the rail chair and rails;

Fig. 3 is a plan view of the rail chair.

The rail chair may be made in any well known economical manner, as by casting or forging and comprises a single piece of metal of rectangular shape having a portion 10 adapted to support the main or traffic rail and a portion 11 inclined thereto, which is adapted to support the guard rail. It is not essential that the rail chair be rectangular in shape, or that it have a single inclined bearing portion, as it is within the intent of the invention to have a rail chair of a different outline, and with more than one inclined guard rail bearing portion.

At one end of the chair is a raised portion or shoulder 12 adapted to bear against the outer edge of the inside traffic rail and to prevent its movement in one direction, and at the upper end of the inclined portion 11 is a raised portion or shoulder 13 adapted to prevent lateral movement of the guard rail in the opposite direction. Also provided at the foot of the inclined portion of the chair, is an upwardly projecting flange or shoulder 14, integral with the main body of the chair and which is adapted to bear against the outside edge of the lower flange of the guard rail to prevent lateral movement of the same toward the inside of the curve. Suitable openings for spikes are shown at 15, and ordinary spikes 16 serve to securely anchor the chair to the railroad tie.

The chair described above is simple, strong, easy to manufacture, and fulfills all the requirements necessary for a rail chair of its character. No guard rail of special shape is required, but ordinary rails may be used therewith. By tilting the guard rail in the manner shown, its head is brought to the exact distance required from the head of the main or traffic rail, while its base is at the same time securely fastened, and the

rail is firmly mounted to resist the overturning thrust of the car wheels.

Having thus described my invention what I claim is:

- 5 1. A railroad rail chair formed of a single piece of metal having a bearing portion for a main or traffic rail, and an inclined portion adjacent thereto for supporting a guard rail, for the purpose set forth.
- 10 2. A railroad rail chair formed of a single piece of metal, having a bearing portion for a main rail and a portion inclined thereto for supporting a guard rail, and projecting portions comprising shoulders adapted to contact with the guard rail to prevent lateral movement thereof, one of said shoul-
- 15

ders being adapted to contact with the edge of the rail only.

3. A railroad rail chair formed of a single piece of metal, having a bearing portion for 20 a main rail and a bearing portion inclined thereto for a guard rail, projecting shoulders at the top and bottom of the inclined portions adapted to contact with the guard rail to prevent lateral movement thereof, 25 one of said shoulders being adapted to contact with the edge of the rail only and a projecting shoulder adapted to abut against the outer edge of the main rail to prevent its movement away from the guard rail. 30

In testimony whereof I affix my signature.

ORLANDO K. MORGAN.
